UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,372,306.

Specification of Letters Patent. Patented Mar. 22, 1921.

Application filed October 22, 1919. Serial No. 332,433.

To all whom it may concern:

Be it known that I, WILLIAM L. MCGRATH, a citizen of the United States, residing at Elmira, in the county of Chemung and State 5 of New York, have invented certain new and useful Improvements in Engine-Starters, of which the following is a specification.

My invention relates to a starter for starting an engine, more particularly an internal combustion engine, and the same pertains to the drive or transmission thereof located between a prime mover such as an electric motor and a member or part of the engine to be started such as the fly wheel thereof. 15 The object of my invention is to provide a novel, efficient and reliable construction of drive of the type in which screw shaft means are employed. The various features of advantage and utility in my construction of 20 drive will be apparent from the description hereinafter given.

In the drawing Figure 1 is a central sectional elevation of a starter system including a drive embodying my invention; and Fig. 25 2 a similar view but illustrating a modified form of construction.

It will be understood that the embodiment of my invention as herein shown is selected as one of a number of forms in which the 30 same may be embodied, and also that while I have shown my invention in connection with the so-called single reduction type of drive in which the screw shaft is an extended armature shaft, my invention is equally 35 applicable to the double reduction type in which the screw shaft is driven indirectly by the motor.

Referring to Fig. 1 the electric motor 1 has an extended armature shaft which 40 constitutes the driving shaft of the drive or transmission. For convenience in manufacture this driving shaft is made in two parts, to wit, a screw shaft 2 adjacent the motor and a plain shaft 3 secured together in axial 45 alinement in suitable manner as by screw-threading of one into the other as at 4. Upon the screw shaft is mounted the control member or nut 5 which is operatively connected for control and driving purposes 50 with the driving member or pinion 6 which is adapted to mesh when advanced longitudinally to the right with the engine member such as the fly wheel 7. This pinion is mounted upon the plain portion 3 of the 55 driving shaft and is adapted to slide there-

upon longitudinally and also to rotate therewith after being meshed with the fly wheel.

The operating connection between the nut and the pinion consists of a cylindrical shell or cup 8 secured at one end to the nut by 60 means of the screw 9, and at its other end through the friction clutch formed of the sets of plates 10 and 11, the former being connected with the shell and the latter with the pinion. The plates 10 are interlocked 65 with the shell by extending into the longitudinal openings 12 therein. The plates 11 are interlocked with the pinion by extending into longitudinal grooves 13 in the extended hub portion 14 of the pinion. This hub 70 portion is provided with two stops, one a stop ring 15 pressed upon said hub adjacent the teeth of the pinion, and the other a ring 16 screwed onto the outer end of this hub. The friction plates are thus located 75 between these two stop rings and confined between spring 17 and a spring ring 40 which is locked in the shell.

Within the shell 8 there are located two separate coiled springs 17 and 18, the former 80 being heavier and of the greater diameter. The spring 17 is interposed between the base of the shell 8 and the friction clutch and its function is to give the desired tension to such clutch. The other coiled spring is in- 85 terposed between the shell and the end of the pinion hub, and its function is to hold the pinion in the normal position shown but adapted to yield in the event that the pinion teeth should strike the fly wheel teeth 90 end to end, thereby coming to a stop where- as the nut 5 keeps on moving outwardly.

The drive is supported not only by the motor through its extended armature shaft 2, but also by an inclosing casing 19 which 95 has a bearing 20 for the outer end of the driving shaft.

Describing a cycle of operation and starting with the parts in their normal position shown, when the motor is operated the driving shaft 2, 3, is rotated, with the result that the nut 5 is caused to advance or move longitudinally to the right, together with all of the associated parts, including the pinion 6, which thereby becomes meshed with the fly 105 wheel. When the nut 5 has traveled its full distance longitudinally, and been stopped by the stop ring 21 on the driving shaft, the longitudinal movement of the parts will 110 cease and such nut and pinion will then

partake of the rotary movements of the driving shaft and the fly wheel will thereupon be rotated. When the engine starts on its own power the pinion will be automatically demeshed and returned to normal position.

The construction and arrangement of parts are such that the pinion and the associated parts will retain the relative position 10 shown in Fig. 1 until mesh with the fly wheel is obtained except that in case the pinion teeth should abut the fly wheel teeth end to end the parts are permitted to yield by reason of the clearance space indicated at 22 between the stop ring 15 and the outermost 15 friction plate, such yield being against the tension of the spring 18. At the time of full mesh of the pinion with the fly wheel the pinion and its hub are at their outermost 20 position toward the right with respect to the friction clutch and the shell 8 with the stop ring 16 immediately adjacent the innermost friction plate. After the pinion has meshed 25 with the fly wheel and the nut 5 continues to advance, the spring 17 will be the more tightly compressed against the friction clutch, for which purpose the shell 8 which thus continues to move with the nut 5 has sufficiently deep openings 12 to permit of 30 this further movement.

In Fig. 2 I have shown a modified form of construction according to which the motor 23 has an extended armature shaft 24 provided with an outer bearing 25. This 35 shaft is a driving shaft and upon it toward its outer end is mounted a hollow screw shaft 26 provided at its outer end with a stop nut 27 and at its inner end with a driven head or disk 28. Upon the screw 40 shaft is mounted a driving member or pinion 29 which is adapted to mesh with the teeth of the fly wheel 30.

To the head 28 there is secured a shell 31 similar to the shell 8 and containing similar 45 parts such as the friction clutch and the coiled springs. For instance the clutch is composed of the friction plates 32 and 33 which form the driving connection between the shell 31 and a driving head 34 which is 50 in the form of a sleeve or collar secured to the shaft 24 by the key 35. A flanged plate 36 is secured to the shaft to form the right-hand abutment for the friction plates and while the left-hand abutment is formed by 55 a stop ring 37 screwing onto the outer end of the sleeve 34. The outer heavy spring is shown at 38 and the inner light spring at 39.

Describing a cycle of operation of the Fig. 2 structure, and starting with the parts 60 in their normal position shown, when the motor is operated the shaft 24 is rotated thereby rotating the screw shaft 26 through the driving head 34, friction clutch 33, shell 31 and driven head 28. As a result the 65 pinion 29 will be advanced longitudinally to

the left along the screw shaft and into mesh with the fly wheel. When the engine has started on its own power the pinion will be automatically demeshed and returned to normal position. In the event that the 70 pinion teeth and the fly wheel teeth should abut end to end the screw shaft will yield longitudinally to the right against the tension of the spring 39, it being understood that the casing 31 will move longitudinally 75 with the screw shaft.

I claim:

1. An engine starter drive comprising a rotatable shaft, a driving member actuated by such shaft in its rotation for longitudinal movement thereof and rotary movement therewith, and adapted in its longitudinal movement to engage a member of the engine to be started, a friction clutch arranged in the line of transmission of power, yielding means coöperating with the clutch to apply pressure thereto, and independent yielding means for resisting relative longitudinal movement of the shaft and driving member, one with respect to the other, and tending 90 to move the driving member toward the engine member.

2. An engine starter drive comprising a rotatable shaft, a driving member actuated by such shaft in its rotation for longitudinal movement thereof and rotary movement therewith, and adapted in its longitudinal movement to engage a member of the engine to be started, a friction clutch arranged in the line of transmission of power, 95 coöperating with the clutch to apply tension thereto and adapted to resist relative longitudinal movement of the shaft and driving member, and a comparatively light spring for resisting 100 relative longitudinal movement of the shaft and driving member, one with respect to the other and tending to move the driving member toward the engine member.

3. An engine starter drive comprising a 110 rotatable shaft, a pinion actuated thereby in its rotation for longitudinal movement thereof and rotary movement therewith, and adapted in its longitudinal movement to engage a member of the engine to be started, a friction clutch arranged in the line of transmission of power, yielding means coöperating with the clutch to apply tension thereto and adapted to resist relative longitudinal movement of the shaft and driving 115 member, and a spring for resisting relative longitudinal movement of the shaft and driving member, one with respect to the other and tending to move the driving member toward the engine member.

4. An engine starter drive comprising a rotatable shaft, a driving member actuated by such shaft in its rotation for longitudinal movement thereof and rotary movement therewith, a friction clutch mounted on the 130

- driving member, yielding means coöperating with the clutch to apply pressure thereto, said driving member being adapted, when moved longitudinally to engage a part of the engine to be started, and separate yielding means for cushioning the parts of the drive in case such driving member abuts the engine part in improper manner without effecting operative engagement.
10. 5. An engine starter drive comprising a rotatable shaft, a driving member actuated by such shaft in its rotation for longitudinal movement thereof and rotary movement therewith, a friction clutch mounted on the driving member, yielding means coöperating with the clutch to apply pressure thereto, said driving member being adapted, when moved longitudinally to engage a part of the engine to be started, and a spring 70 separate from said yielding means of the clutch for cushioning the parts of the drive in case such driving member abuts the engine part in improper manner without effecting operative engagement.
15. 6. An engine starter drive comprising a rotatable shaft, a driving member mounted to slide longitudinally thereon and to rotate therewith, a control member mounted on said shaft for longitudinal movement there- 75 on and rotary movement therewith, and friction clutch mechanism mounted on the driving member, the driving member being connected with such mechanism positively for rotary movement with the shaft and 80 slidily for its said longitudinal movement thereof.
20. 7. An engine starter drive comprising a rotatable shaft, a driving member mounted to slide longitudinally thereon and to rotate therewith, a control member mounted on said shaft for longitudinal movement there- 85 on and rotary movement therewith, and friction clutch mechanism mounted on the driving member, the driving member being connected with such mechanism positively for rotary movement with the shaft and 90 slidily for its said longitudinal movement thereof.
25. 8. An engine starter drive comprising a rotatable shaft, a driving member mounted to slide longitudinally thereon and to rotate therewith, a control member mounted on said shaft for longitudinal movement there- 95 on and rotary movement therewith, and friction clutch mechanism mounted on the driving member, the driving member being connected with such mechanism positively for rotary movement with the shaft and 100 slidily for its said longitudinal movement thereof, and means for limiting said sliding movement of the clutch mechanism and 105 driving member relative to each other.
30. 9. An engine starter drive comprising a rotatable shaft, a driving member mounted to slide longitudinally thereon and to rotate therewith, a control member mounted on said shaft for longitudinal movement there- 110 on and rotary movement therewith, and friction clutch mechanism between the two members, the driving member being connected with such mechanism positively for 115 rotary movement with the shaft and slidily for its said longitudinal movement thereof, and rings arranged on the driving member on either side of the clutch.
35. 10. An engine starter drive comprising a rotatable shaft, a driving member mounted to slide longitudinally thereon and to rotate therewith, a control member mounted on said shaft for longitudinal movement there- 120 on and rotary movement therewith, and friction clutch mechanism mounted on the driving member, the driving member and clutch mechanism being interlocked for rotary driving of the driving member and for the relative longitudinal movement thereof.
40. 11. An engine starter drive comprising a rotatable shaft, a driving member mounted to slide longitudinally thereon and to rotate therewith, a control member mounted on said shaft for longitudinal movement there- 125 on and rotary movement therewith, and friction clutch mechanism mounted on the driving member, said driving member and clutch mechanism being connected for rotary driving of such driving member and for relative longitudinal movement.
45. 12. An engine starter drive comprising a rotatable shaft, a driving member mounted to slide longitudinally thereon and to rotate therewith, a control member mounted on said shaft for longitudinal movement there- 130 on and rotary movement therewith, a casing secured to the control member, and clutch mechanism coöperating with the casing, one having relative longitudinal movement with respect to the other, such mechanism being operatively connected with the driving member.
50. 13. An engine starter drive comprising a rotatable shaft, a driving member mounted to slide longitudinally thereon and to rotate therewith, a control member mounted on said shaft for longitudinal movement there- 135 on and rotary movement therewith, a casing secured at one end to the control member, and clutch mechanism operatively connected with the other end thereof, the casing and clutch mechanism have relative longitudinal movement, one with respect to the other, and the clutch mechanism being operatively connected with the driving member.
55. 14. An engine starter drive comprising a rotatable shaft having a screw threaded portion and a plain portion, a pinion adapted to slide on such plain portion and to be rotated therewith, a nut threaded on the screw-threaded portion, and driving connections 140 between the nut and pinion including a friction clutch composed of plates one set of 145

which is interlocked with the pinion to permit its longitudinal movement relative to the clutch and the other set of which is operatively connected with said nut.

5 15. An engine starter drive comprising a rotatable shaft having a screw-threaded portion and a plain portion, a pinion adapted to slide on such plain portion and to be rotated therewith and having a hub portion,

10 a nut threaded on the screw-threaded portion, and driving connections between the nut and pinion including a friction clutch, comprising plates directly attached to the pinion hub, the plates and hub having a relative sliding movement, one upon the other.

15 16. An engine starter drive comprising a rotatable shaft having a screw-threaded portion and a plain portion, a pinion adapted to slide on such plain portion and to be rotated therewith, a nut threaded on the screw-threaded portion, and driving connections between the nut and pinion including a friction clutch, which is directly attached to the pinion, such pinion having a longitudinal

20 movement relative to the clutch.

25 17. An engine starter drive comprising a rotatable shaft, a driving member mounted to slide longitudinally thereon and to rotate therewith, a control member mounted on

30 said shaft for longitudinal movement thereon and rotary movement therewith, a shell fixed at one end to said control member, and friction clutch mechanism mounted on the driving member and connected with the

35 other end of the shell for rotary movement and also for relative longitudinal movement, one with respect to the other.

18. An engine starter drive comprising a rotatable shaft having a screw threaded portion and a plain portion, a pinion adapted

45 to slide on such plain portion and to be rotated therewith, a nut threaded on the screw threaded portion a shell fixed at one end to said nut and projecting toward the pinion, and a friction clutch mechanism mounted on the pinion and operatively connected with the shell for positive rotary movement and for relative longitudinal movement one with respect to the other.

45 19. An engine starter drive comprising a 50 rotatable shaft having a screw threaded portion and a plain portion, a pinion adapted to slide on such plain portion and to be rotated therewith, a nut threaded on the screw threaded portion, a shell fixed at one end to 55 said nut and provided at its other end with longitudinal slots and a driving connection between the nut and pinion including a friction clutch composed of plates, one set of which is provided with tongues engaged by 60 said slots and interlocked therewith and the other set of which is provided with tongues interlocked with said pinion.

20. An engine starter drive comprising a 65 rotatable shaft, a driving member actuated by such shaft in its rotation for longitudinal movement thereof and rotary movement therewith and adapted in its longitudinal movement to engage a member of the engine to be started, a friction clutch arranged in 70 the line of transmission of power, and two independent yielding means for resisting relative longitudinal movement of the shaft and driving member, one with respect to the other, such means comprising a comparatively light spring and a comparatively heavy spring, said two springs acting successively for resisting such relative movement.

75 WILLIAM L. McGRATH.
